UNITED STATES PATENT OFFICE.

FRANK C. ANDERSON, OF CINCINNATI, OHIO, ASSIGNOR TO THE AMERICAN VALVE & METER COMPANY, OF CINCINNATI, OHIO, A CORPORATION OF OHIO.

INTERLOCKING AND TARGET-OPERATING MECHANISM FOR SWITCH-STANDS.

1,276,157.

Specification of Letters Patent.

Patented Aug. 20, 1918.

Application filed March 27, 1916. Serial No. 86,959.

To all whom it may concern:

Be it known that I, FRANK C. ANDERSON, a citizen of the United States, and a resident of Cincinnati, in the county of Hamilton 5 and State of Ohio, have invented certain new and useful Improvements in Interlocking and Target-Operating Mechanism for Switch-Stands, of which the following is a specification.

10 My invention relates to switch stands; and its object is to provide a switch stand with an interlocking mechanism and a target mechanism and to simultaneously operate both of these mechanisms, preliminary to 15 the throwing of the switch.

My invention consists in the combination of parts and in the details of construction and arrangement of parts, as will herein be more fully described and claimed.

20 In the drawings:

Figure 1 is a general perspective view of a switch stand, its interlocking mechanism and its target, provided with my invention;

25 Fig. 2 is a detail perspective view of the target connecting rod;

Fig. 3 is a similar view of the stem with the connecting rod shown by dotted lines in its position that it has while being connected to the stem;

30 Fig. 4 is a detail perspective view of the bell-crank;

Fig. 5 is a similar view of the head and plunger;

Fig. 6 is a plan view of part of the switch 35 stand and part of the target and the interlocking and target operating mechanism; and

Fig. 7 is a vertical longitudinal section on a plane corresponding to the line 7—7 of 40 Fig. 6, only the lower part of the switch stand and connections thereto being shown.

The switch stand 1 has the main shaft 2 journaled vertically in it, being held in upper and lower bearings by caps 3 and 4, 45 respectively. Below the lower bearing this shaft has the crank 5 with the crank pin of which is adapted to receive the connecting rod 5', which is connected to the point rails 6 of the switch. Above the upper bearing,

50 said main shaft 2 has, fixed on it, the fulcrum-head 7 bearing down against the upper side of the upper bearing. The fulcrum-head 7 has the switch-operating lever or handle 8 pivotally swinging on the pivot 9.

55 The top of this switch stand 1 comprises the

horizontal plate 10 which has slots 11, 11' and 11'', the first two being diametrically opposite on a line through the center of the main shaft 2 and substantially parallel with the track rail, being thus 180° apart; 60 while the third slot 11'' is at the rear of the stand half way between or 90° from the slots 11 and 11'. The handle or lever 8 is adapted to engage in any one of these slots. As the switch stand is here shown, the main 65 shaft 2 is adapted to be turned through an angle of 90° to throw the switch, and the handle or lever 8 is adapted to engage in the slot 11 when the switch is closed as shown, or in the slot 11'' when the switch is 70 opened. When the switch stand is to have its main shaft 2 turned through 180° to throw the switch, the middle slot 11'' is omitted. The other slot 11' comes into use, and the slot 11 into disuse, where the stand 75

is to have its shaft 2 operated through only 90°, but where it is desired that the handle or lever 8 be at the other side of the stand when it has closed the switch, as is the case when the switch turns out in the opposite 80 direction from that here shown. Such an arrangement is necessary in connection with the proper arrangement of the interlocking mechanism. For this reason also the crank 5 is made to fit in a head 2' on the lower end 85 of the shaft 2 in any one of the four different positions which the switch stand may be required to occupy, accordingly as the switch turns out to the right or to the left in either one of two directions along the track. 90

The switch stand 1 has the stop lugs 12 under the slots 11 and 11', respectively, to stop the lever 8 when it is brought down into its slot 11 or 11'. The lug 13 on the lever 8 projects through an opening 13' in the end 95 of the fulcrum-head 7 when the lever is in the slot 11 or 11', this lug having an opening 13'' to receive the part of the padlock.

Whether the main shaft 2 is operated through 180° or 90°, or whether it has any 100 other degree of rotation, is immaterial to the operation of the parts comprising my invention, because the operation of my invention takes place entirely during the preliminary movement of the handle or lever 8 when it is raised out of the slot 11 or 11', as the case may be. The mechanism so far described is similar to previously disclosed apparatus in switch stands.

As switch stands are usually constructed, 110

the target is placed on an upward extension of the main shaft 2, and the target is not turned until the main shaft is turned and throws the switch; but where the target is to be operated preliminarily to the switch throwing movement, a separate shaft 15 is journaled vertically, parallel with the main shaft 2, in upper and lower brackets 16 and 17, which are bolted to the switch stand 10 along with the caps 3 and 4, respectively, of the upper and lower bearings of the shaft 2. These brackets not only extend outwardly some distance from the main shaft but are also offset toward one side of the switch stand. Below the lower bracket 17 an arm 18 is screwed into a hub 18' pinned or otherwise suitably fixed to the target shaft 15. A lock nut 18" prevents unscrewing of the arm 18 from the hub 18'. A collar 15' is fixed on the shaft 15 above the upper bracket 16 to support the shaft. The upper end of the target shaft carries the blades 19 and 20 extending at right angles to each other and adapted, respectively, 25 when turned in directions crosswise of the track to signal "safety" or "danger."

It will thus be seen that the target shaft 15 is to be rotated through only 90° whether the main shaft 2 be rotated through 90° 30 as shown, or through 180° as may be desirable.

The interlock and target operating lever 21 has a pivot 22 in one of the two stops 23 and 24 which are provided on the plate 10 35 for the fulcrum-head 7. This pivot 22 is substantially concentric with the pivot 9 of the switch-operating lever or handle 8. The lever 21 extends down and has a lug 25 that projects over toward the switch operating lever 8 to enter a recess 26 in said switch operating lever when it is brought over toward the interlock and target operating lever.

The switch stand 1 is mounted on the head blocks 27, and one of these, close to the switch stand, between the switch stand and the track, is gained or recessed and receives a housing 28. The point-rail 6 of the switch has a guard 29 bolted to it, as seen in Fig. 50 1, and the interlocking-bar 30 is secured to this guard 29 by means of nuts 31, flanking the guard and adjustable along a rounded part 32 of the bar 30. This bar 30 slides through a part 28' of the housing 28 that 55 extends outside the head block 27. A guide 33 for the interlocking-bar 30 is also provided on the head block 27 about mid-way between the housing 28 and the track, to reinforce said bar and render the operation 60 of the apparatus more accurate.

The housing 28 has, integral with it and extending out from all of its sides, a flat plate 34 which lies flat on the upper side of the head block 27, completely covering the 65 recess or gain in the head block and being

screwed or otherwise suitable secured to the head block. It also has a depending web 34' to close the inner end of the gain in the head block 27.

Sliding horizontally in the housing 28, 70 at right angles to the interlocking-bar 30, is the interlocking-plunger 35. The interlocking-bar 30 has an opening 36, and this interlocking-plunger 35 can extend through this opening and out through the outside of 75 the housing 28 when the point-rail 6 is drawn up close to the stock-rail of the track and is perfectly safe for traffic. The parts are so made however, that if the point-rail 6 is, for any reason, left any appreciable distance away from the stock-rail, the plunger 80 35 cannot enter the opening 36.

Extending up from the upper side of the plate 34, is a crank-casing 37, with a cover 38 secured to its top and holding in bearings 85 formed in said casing and cover the transverse shaft 39, which makes up, with the arms 40 and the arms 41, a bell-crank of integral construction. The plunger 35, sliding in the part 28' of the housing 28 outside the 90 head block and in an inner bearing 28" that extends down from the plate 34, has its inner end part fixed to a head 42, by extending through a downwardly extended lug 42' on said head with a transverse pin 42" through 95 it and the lug. The main part of the head 42 is horizontal, and about on the level of the plate 34 that is around the outside of the housing; the bottom of the casing being entirely open from end to end, leaving a space 100 for this head 42 to slide in. The lug 42' is of much less width than the main part of the head; and at the sides of the main part are recesses 43, in which engage the lower end parts of the arms 40, in such a manner that, 105 as the arms 41 of the bell-crank are raised, these arms 40 will pull the plunger 35 back from the interlocking bar 30.

The head 42 also has an upwardly extending lug 44, also somewhat narrower 110 than the main part of the head, so that it may pass between the arms 40, as they reciprocate the head. A stem 45 extends through and has a bearing in the inner or rear end 37' of the crank casing 37, with 115 a reduced part extending through an opening in the upwardly extending lug 44 of the head 42, and with a nut 46 screwed onto a further reduced and threaded terminal part of the stem, where it extends through said lug. To keep the nut 46 from turning, I prefer to provide the head 42 with ribs 47, that flank the nut 46. To keep the stem 45 from turning, I prefer to place a rivet or pin 48 down through the lug 44 and the part 120 of the stem 45 lying therein. The part of the stem 45 outside the housing has an upright widened part 49 with an elongated and widened lower horizontal part 50, and a short but wide upper horizontal part 51, 125

extending rearwardly from it; while the lower part 50 has, some distance to the rear of the rear termination of the upper part 51, an upright stud 52. Preferably this stem 45 and these parts 49, 50, 51, 52, are formed integral. A connecting rod 53 has an eye 54 fitting over the stud 52, at one end; and its other end is screwed into a fork 55 that receives the arm 18 of the target shaft 15 between its members, with a pin 56 passing down through the members and the arm. A lock nut 57 prevents the stem 53 from turning in the fork 55. The eye 54 of the connecting rod 53 has the spur 58 extending forwardly under the short upper part 51 of the stem 45 at all times while the stem is connected to the arm 18 by the connecting rod; the part 51 being wide enough to be engaged by this spur upon rising of the connecting rod 53 in any of its operative positions while making the above connection. The connecting rod 53 has its eye 54 slipped over this stud 52 while it is turned far out of operative position, before connecting it to the arm 18, as is indicated by the dotted lines in Fig. 3.

About opposite the lug 25, on the interlock and target-operating lever 21, is a boss 59, in which is a stud 60, extending out over the above described interlock and target-operating mechanism. A connecting rod 61 has an eye 62 around this stud 60, held thereon by a nut 63. This connecting rod 61 extends down, and a bridle 64 has an upwardly extending hub 65 into which the lower end of the rod 61 is screwed and held by a lock nut 66. This bridle 64 lies between the end parts of the arms 41, with a pin 67 through it and said arms.

With the parts thus arranged, when it is desired to open the switch, finding the lever 8 and the other parts in the positions shown in Fig. 1, the operator removes the padlock from the opening in the lug 13, and raises the lever 8 to its horizontal position, so as to release it from the slot 11. In doing this, he raises the interlock operating lever 21 along with the lever 8, by the engagement of the lug 25 in the recess 26 in said lever 8. Raising this lever 21 thus to its horizontal position, it operates, through the connection by means of the rod 61 and bridle 64, to raise the arms 41 of the bell-crank, which, as before described, withdraws the plunger 35 from the interlocking bar 30. At the same time, the head 42 will operate through the stem 45 and connecting rod 53 and arm 18 to turn the target shaft 15 and its target elements 19 and 20 through the required angle of 90°, to change the target from "safety" to "danger" position.

If desired, the interlocking plunger 35 may be provided with a locking mechanism consisting of a vertical bolt 68, which fits in a notch or recess 69 in the upper side of the

plunger 35 between the parts 28' and 28'' of the housing 28, having a casing 70 formed in this housing 28, between these parts, and extending up above the plate 31 of the housing, and having in its top an opening 71 for the bolt 68 to pass through. Above the top of the casing 70, the bolt has a head 72, in the front side of which is a recess 73. At the other or front end of the part 34 of the casing, over the part 28', are upwardly extending lugs 74, between which is pivoted a treadle 75 by means of a pin 76. This treadle has an arm 77 extending upwardly and rearwardly from the part which has the pin 76 passing through it; and the free end 80 of this arm 77 is in the form of a substantially spherical knob 78 fitting in the recess 73 of the head 72 on the bolt 68. Thus, when the treadle 75 is depressed, the bolt 68 will be raised out of the notch 69 in the plunger 35. To normally press the bolt 68 down in this notch 69, a helical spring 79 is passed around the bottom 68, inside the casing 70, between the lower side of the top of the casing and a downwardly cupped washer 80 on the bolt, which is held thereon by a pin 81 passing through the bolt inside the cupped part of the washer, and prevented from leaving its position by the rim of this cupped part at both sides. The pin 81 is inserted into the bolt 68 through an opening 82 in the part 28'', while the cupped washer 80 is raised; and when the pin has reached its position, the spring 79, is allowed to force the washer 80 down over the pin. Thus the pin and washer maintain each other in position.

Having fully described my invention what I claim as new and desire to secure in my Letters Patent is:

1. In interlocking and target-operating mechanisms for switch stands, in combination with an interlocking plunger adapted to lie below the upper surface of a head block, a housing adapted to be mounted on said head block over said plunger, and means adapted for connection to the operating mechanism of a switch stand and extending into said housing in operative engagement with said plunger, a stem extending through and guided by a wall of said housing and operatively connected to said plunger, and a connecting rod pivoted to said stem outside the housing for operative connection of said mechanism to a rotary target.

2. In interlocking and target-operating mechanism for switch stands, in combination with an interlocking plunger adapted to lie below the upper surface of a head block, a housing adapted to be mounted on said head block over said plunger, and means adapted for connection to the operating mechanism of a switch stand and extending into said housing in operative engagement with said

plunger, a stem extending through and guided by a wall of said housing and operatively connected to said plunger, a connecting rod for connection to a rotary target, a connection for said connecting rod and said stem, and means whereby said connection is maintained when said connecting rod is in

position for operative connection to said target but permitting disconnection when the connecting rod is swung out of said position. 10
